COMBINED PIPE WRENCH AND VISE

Edgar Seaver, Burr Oak, Mich.

Application November 3, 1947, Serial No. 783,700

17 Claims. (Cl. 81—53)

1
This invention relates to improvements in combined pipe wrench and vise.

The principal objects of this invention are:

First, to provide a tool which may be used conveniently as a pipe wrench or a pipe vise.

Second, to provide a pipe wrench of the self-tightening or gripping type which is easily opened to release the pipe and which may be mounted on a stationary support and utilized as a pipe vise.

Third, to provide a pipe wrench with a link mounted lower jaw which cooperates with an adjustable and swingable upper jaw so that the wrench will have a strong self-tightening gripping action when torque is applied to the wrench and so that the jaws will open wide when the wrench is moved oppositely from the torque applying direction.

Fourth, to provide a pipe wrench in which the grip or pressure of the jaws may be greatly increased by the use of a separate wrench or tool.

Fifth, to provide a pipe wrench having two adjustments for tightening the jaws of the wrench, whereby one adjustment may be used to determine the approximate spacing of the wrench jaws and the second adjustment may be used to obtain a high clamping force between the jaws.

Sixth, to provide a wrench having two adjustments for tightening the jaws of the wrench, one of which adjustments has an unconnected thrust engagement with the jaws to automatically loosen the jaws when the wrench is moved oppositely from its working direction.

Other objects and advantages pertaining to the details and economies of my invention will be apparent from a consideration of the following description and claims.

The drawings, of which there are two sheets, illustrate a preferred form of my wrench.

Fig. 1 represents a side elevational view of my wrench mounted on a stationary support for use as a pipe vise, the support and portions of the handle of the vise being illustrated in cross section.

Fig. 2 is a longitudinal cross sectional view along the line 2—2 in Fig. 3.

Fig. 3 is a horizontal cross sectional view along the broken line 3—3 in Fig. 2.

Fig. 4 is an elevational view of the rear edge of my wrench.

Fig. 5 is a fragmentary cross sectional view along the line 5—5 in Fig. 2.

Fig. 6 is a fragmentary cross sectional view along the line 6—6 in Fig. 2.

2
Fig. 7 is a perspective view of the thumb wheel for adjusting the spacing of the jaws of my wrench.

Fig. 8 is a perspective view of the upper dog for adjusting the position of the thumb wheel shown in Fig. 7.

Fig. 9 is a perspective view of the lower dog which cooperates with the upper dog in positioning the thumb wheel.

10 Fig. 10 is an elevational view of the thrust link for determining the position of the dogs and thumb wheel illustrated in Figs. 7 to 9.

My wrench consists generally of a body member 1 upon which are mounted the lower jaw 2, upper jaw 3 and a lever arm or handle 4. The body member 1 is provided with a hexagonal or other non-circular base 5 arranged to be received in a suitable socket 6 secured to a fixed base such as a plumber's truck as illustrated in Fig. 1. The upper portion of the body 1 is bifurcated as at 7 providing spaced side arms 8 arranged to receive the jaw members as will be more particularly described presently.

The side arms 8 are parallel and of similar 25 outline being provided with rearwardly projecting nose portions 9 spaced downwardly from the tops of the side arms. The nose portions 9 are apertured to receive the pivot pin or bolt 10 as is most particularly shown in Figs. 3 and 5. One 30 of the nose portions 9 defines a non-circular aperture for non-rotatably receiving the non-circular portion 11 of the pin 10.

The upper portions of the side arms 8 are apertured, as at 12, at a point spaced upwardly and 35 forwardly from the aperture 10 and are arranged to receive the pivot pin 13. One of the apertures 12 is non-circular to non-rotatably receive the non-circular portion 14 of the pin 13. (See Fig. 6.)

40 The lower jaw 2 is pivotally mounted by the pin 15 extending between the bifurcated end portions of a link 16. The lower end of the link 16 extends between the upper portions of the side arms 8 and is pivotally supported on the pin 13.

45 It will be noted from Fig. 6 that the tongue portion 17 of the lower jaw is machined to bear against the base of the bifurcation in the link 16, so that forces applied to the lower jaw will be transmitted directly to the link without placing undue stress on the pivot pin 15. The side arms of the body are preferably slotted as at 18 (see Figs. 1, 2, and 6) and an arcuate bearing plate 19 is secured as by welding in the slots to form an abutment for the lower end of the link 16. Thrust forces on the link 16 are thus trans-

mitted directly to the side arms 8 without excessive stress on the pin 13. The lower end of the link 16 is curved, as shown in Fig. 2, to seat against the thrust plate 19.

The upper jaw 3 is provided with a depending arm 20 of generally rectangular cross section but having the adjusting threads 21 formed on the front and rear edges thereof and having the guide slots 22 formed on the sides thereof. The threads 21 are arranged to receive and engage the internally threaded thumb wheel 23 after the manner of an ordinary pipe wrench. The thumb wheel 23 defines an annular groove 24 within which the retained band 25 is received. The ends of the retaining band 25 are secured to the nose portions 9 of the side arms by the pivot pin 10 so that the thumb wheel 23 and upper jaw 3 are rotatably mounted on the body of the wrench.

The lower portion of the thumb wheel 23 defines a series of radially extending holes 26 in which a leverage pin may be inserted for tightening or loosening the thumb wheel. The upper and lower ends of the thumb wheel are beveled inwardly, as at 27, to receive the undercut nose portions 28 of an upper coupling 29 and a lower coupling 30.

As is most clearly shown in Figs. 8 and 9, the coupling 29 defines a central aperture 31 and has a bifurcated lower end 32 defining the aligned apertures 33. The aperture 31 is arranged to pass the pivot pin 10 previously described as being non-rotatably mounted in the nose portions 9 of the side arm.

The coupling 30 is provided with an upwardly extending tongue 34 defining an aperture 35 and arranged to fit between the bifurcations 32 of the upper coupling. A pin 36 connects the upper and lower couplings. It will be noted that the tongue 34 is arranged to bear against the base of the bifurcated portion of the upper coupling but that the tongue is curved so that the undercut portions 28 of the two couplings may be rotated away from each other to assemble and disassemble the couplings on the beveled portions 27 of the thumb wheel. The forward side of the lower coupling 30 is slotted as at 37 and defines the aligned apertures 38 for receiving a pin 39. The slot 37 is arranged to receive the flat cylindrical head portion 40 of the thrust pin 41 and the head portion 40 is apertured for receiving the connecting pin 39. The rear side of the lower coupling is arranged to bear against the front edge of the arm 20 as is most clearly shown in Fig. 2.

The side arms 8 of the body define the aligned apertures 42 which are arranged to receive the cylinder 43 secured in place by the screw 44. The cylinder 43 defines an internally threaded transversely extending aperture 45 which is arranged to engage the threads on the adjusting bolt 46. The shank of the adjusting bolt 46 is hollow and adapted to receive the shank of the pin 41 so that the collar 47 on the pin bears against the end of the adjusting bolt 46.

The depending arm 20 of the upper jaw is thus adjustably carried by the thumb wheel 23 which is in turn swingably mounted on the side arms of the wrench body by the couplings 29 and 30 and retaining band 25. The couplings are capable of being adjusted relative to the pivot pin 10 by operation of the adjusting screw 46. In order to further guide the swinging motion of the thumb wheel and upper jaw, a pair of arcuate guide members 48 are secured to the

side arms 8 of the body and located concentric about the pivot pin 10. The upper ends of the guide members 48 are secured to the pivot pin 13 by the nuts 49 on the ends of the pin. The lower ends of the guide members 48 are secured to the side arms 8 by the screws 50. The arcuate portions of the guide members 48 are segmental in cross section as is most clearly illustrated in Figs. 3, 5 and 6, so that the opposed sides of the guide members engage the opposite sides of the arm 20 on the upper jaw and so that the arcuate outer surface of the guide members may be received within the thumb wheel 23.

The upper and lower jaws are slidably connected by means of opposed flanges 51 formed on the rear edge of the lower jaw and engaged in the slots 22 in the sides of the arm 20 of the upper jaw.

In operating my wrench, the thumb wheel 23 may be turned to move the arm 20 axially and adjust the spacing between the upper and lower jaws. With the wrench positioned in a fixed socket, as shown in Fig. 1, the screw 46 may then be backed off to permit the upper jaw to swing downwardly and backwardly into the position shown by the dotted lines, the lower end of the arm 20 swinging between the side arms 8 of the body of the wrench. The backward swinging motion of the upper jaw 3 will correspondingly swing the lower jaw 2 backwardly due to the engagement of the flanges 51 in the slots 22 but due to the spacing between the pivot pins 10 and 13 the lower jaw will be caused to move away from the upper jaw. In this position a pipe or other object may be placed between the jaws and the adjusting screw 46 turned inwardly of the wrench to raise the jaws of the wrench to the vertical position shown in full lines. In turning the adjusting screw 46 inwardly the collar 47 on the pin 41 will be forced to the rear, in turn swinging the couplings 29 and 30 rearwardly and upwardly about the pivot pin 10. The couplings acting against the arm 20 and upper jaw 3 will carry the arm 20 and upper jaw 3 with them. An extremely high gripping pressure may be obtained between the jaws of the wrench by applying a separate wrench to the head of the adjusting screw 46.

When it is desired to use the wrench independently of a support and as a pipe wrench, the adjusting screw 46 may be removed and secured in the bottom of the handle 4, as indicated by the dotted lines 52 in Fig. 1, at which time the couplings 29 and 30 and thumb wheel 23 will be free to swing downwardly about the pivot 10 to open the jaws of the wrench. The thumb wheel may be turned to adjust the spacing between the upper and lower jaws and when the jaws are swung to erected position they will clamp around the pipe or other object, as shown in Fig. 2. Application of torque to the handle of the wrench will cause the jaws to clamp more tightly to the pipe due to the rearwardly offset position of the pivot pin 10 with respect to the pivot pin 13. To loosen the jaws from the pipe it is only necessary to rotate the wrench slightly to the rear or counter-clockwise, as viewed in Fig. 2.

My wrench will thus operate in the same fashion as an ordinary pipe wrench but with an increased amplitude of automatic adjustment of the spacing between the jaws.

The increased amplitude of jaw opening is of great advantage not only in permitting easy engagement of the wrench with the pipe but also

in materially increasing the number of positions in which the wrench may be attached to the pipe. Note that the swinging mount of the jaws permits the jaws to engage the pipe with the body and handle of the wrench in a wide range of angular positions with respect to the jaws and pipe. Thus the jaws can effectively grip a pipe while in the position shown by the dotted lines in Fig. 1 with the handle at an angle with respect to the normal position of the jaws. This is very advantageous when working in crowded places where it may be difficult to find room to swing the handle of the wrench.

A further advantage of my wrench is that the jaws may be positively clamped to a pipe by means of the screw 46 and it is not necessary to maintain a continual gripping strain on the handle as is the case with ordinary pipe wrenches. The V shaped contour of the jaws gives four point contact with the pipe and forces may be applied to the handle that have components parallel or askew to the pipe and handle without loosening the jaws from the pipe. Such forces on an ordinary wrench would cause it to slip off the pipe.

I have thus described a highly practical embodiment of my combined wrench and vise so that others may reproduce the same with such minor modifications of detail as may be desired without further description.

Having thus described my invention, what I claim as new and desired to secure by Letters Patent is:

1. A combined pipe wrench and vise comprising a body member having a shank portion selectively attachable to a handle or non-rotatably mountable in a fixed socket, spaced side arms on said body member having rearwardly projecting nose portions defining aligned apertures, a first pivot pin supported in said apertures, a second pivot pin extending between said side arms and spaced upwardly and forwardly from said first pivot pin, a first coupling pivotally mounted on said first pivot pin, a second coupling pivotally mounted on said first coupling, a thumb wheel defining an internally threaded aperture and having inwardly beveled ends, said couplings having undercut nose portions engageable with the beveled ends of said thumb wheel, an upper jaw member having a threaded arm portion adjustably received in said thumb wheel, a lower jaw member having a sliding connection with said arm of said upper jaw, a link pivotally connected to said lower jaw and having its lower end pivotally mounted on said second pivot pin, an arcuate thrust plate extending between said side arms and bearing against said link, a thrust pin pivotally connected to said second coupling and having a shoulder formed therearound, a cylinder rotatably mounted between the side arms of said body and defining a transverse threaded aperture, an adjusting screw threadingly engaged in said aperture of said cylinder, said adjusting screw being hollow to receive said thrust pin and movable against said shoulder, arcuate guide members secured to said side arms and concentric about said first pivot pin, said guide members extending through said thumb wheel and alongside of said arm on said upper jaw, and an arcuate strap having its ends secured to said first pivot pin and extending around said thumb wheel, said thumb wheel being annularly grooved to receive said retaining strap.

2. A combined pipe wrench and vise comprising a body member having a shank portion selectively attachable to a handle or non-rotatably

mountable in a fixed socket, spaced side arms on said body member having rearwardly projecting nose portions defining aligned apertures, a first pivot pin supported in said apertures, a second pivot pin extending between said side arms and spaced upwardly and forwardly from said first pivot pin, a first coupling pivotally mounted on said first pivot pin, a second coupling pivotally mounted on said first coupling, a thumb wheel defining an internally threaded aperture and having inwardly beveled ends, said couplings having undercut nose portions engageable with the beveled ends of said thumb wheel, an upper jaw member having a threaded arm portion adjustably received in said thumb wheel, a lower jaw member having a sliding connection with said arm of said upper jaw, a link pivotally connected to said lower jaw and having its lower end pivotally mounted on said second pivot pin, a thrust pin pivotally connected to said second coupling and having a shoulder formed therearound, a thrust member rotatably mounted between the side arms of said body and defining a transverse threaded aperture, an adjusting screw threadingly engaged in said aperture of said thrust member, said adjusting screw being movable against said shoulder.

3. A combined pipe wrench and vise comprising a body member having a shank portion selectively attachable to a handle or mountable in a fixed socket, spaced side arms on said body member defining aligned apertures, a first pivot pin supported in said apertures, a second pivot pin extending between said side arms and spaced upwardly and forwardly from said first pivot pin, a first coupling pivotally mounted on said first pivot pin, a second coupling pivotally mounted on said first coupling, a thumb wheel defining an internally threaded aperture and having inwardly beveled shoulders at its ends, said couplings having undercut nose portions engageable with the shoulders of said thumb wheel, an upper jaw member having a threaded arm portion adjustably received in said thumb wheel, a lower jaw member having a sliding connection with said arm of said upper jaw, a link pivotally connected to said lower jaw and having its lower end pivotally mounted on said second pivot pin, a thrust bar pivotally connected to said second coupling and having a shoulder formed thereon, a thrust member rotatably mounted in the side arms of said body and defining a transverse threaded aperture, an adjusting screw threadingly engaged in said aperture of said thrust member, said adjusting screw being movable against said shoulder on said thrust bar.

4. A combined pipe wrench and vise comprising a body member having a shank portion selectively attachable to a handle or mountable in a fixed socket, spaced side arms on said body member defining aligned apertures, a first pivot pin supported in said apertures, a second pivot pin extending between said side arms and spaced from said first pivot pin, a first coupling pivotally mounted on said first pivot pin, a second coupling pivotally mounted on said first coupling, a thumb wheel defining an internally threaded aperture and having inwardly beveled shoulders at its ends, said couplings having undercut nose por-

tions engageable with the shoulders of said thumb wheel, an upper jaw member having a threaded arm portion adjustably received in said thumb wheel, a lower jaw member having a sliding connection with said arm of said upper jaw, a link pivotally connected to said lower jaw and having its lower end pivotally mounted on said second pivot pin, a thrust bar pivotally connected to said second coupling and having a shoulder formed thereon, a thrust member rotatably mounted in the side arms of said body and defining a transverse threaded aperture, an adjusting screw threadingly engaged in said aperture of said thrust member, said adjusting screw being movable against said shoulder on said thrust bar, and an arcuate strap having its ends secured to said first pivot pin and extending around said thumb wheel.

5. A combined pipe wrench and vise comprising a body member having a shank portion selectively attachable to a handle or mountable in a fixed socket, spaced side arms on said body member defining aligned apertures, a first pivot pin supported in said apertures, a second pivot pin extending between said side arms and spaced from said first pivot pin, a first coupling pivotally mounted on said first pivot pin, a second coupling pivotally mounted on said first coupling, a thumb wheel defining an internally threaded aperture and having inwardly beveled shoulders at its ends, said couplings having undercut nose portions engageable with the shoulders of said thumb wheel, an upper jaw member having a threaded arm portion adjustably received in said thumb wheel, a lower jaw member having a sliding connection with said arm of said upper jaw, a link pivotally connected to said lower jaw and having its lower end pivotally mounted on said second pivot pin, a thrust bar pivotally connected to said second coupling and having a shoulder formed thereon, a thrust member rotatably mounted in the side arms of said body and defining a transverse threaded aperture, an adjusting screw threadingly engaged in said aperture of said thrust member, said adjusting screw being movable against said shoulder on said thrust bar, and an arcuate guide member secured to said side arms and concentric about said first pivot pin, said guide member extending through said thumb wheel and alongside of said arm on said upper jaw.

6. A combined wrench and vise comprising a body member having a shank portion selectively attachable to a handle or mountable in a fixed socket, spaced side arms on said body member defining aligned apertures, a first pivot pin supported in said apertures, a second pivot pin extending between said side arms and spaced from said first pivot pin, a two part coupling pivotally mounted on said first pivot pin, a thumb wheel defining an internally threaded aperture and having shoulders on its ends, said coupling having opposed nose portions engageable with the shoulders of said thumb wheel, an upper jaw member having a threaded arm portion adjustably received in said thumb wheel, a lower jaw member having a sliding connection with said arm of said upper jaw, a link pivotally connected to said lower jaw and having its lower end pivotally mounted on said second pivot pin, a thrust bar pivotally connected to said coupling and having a shoulder formed thereon, a thrust member rotatably mounted in the side arms of said body and defining a transverse aperture, an adjusting screw threadingly engaged in said aperture of said

thrust member, said adjusting screw being movable against said shoulder on said thrust bar, an arcuate guide member secured to said side arms and concentric about said first pivot pin, said guide member extending through said thumb wheel and along side of said arm on said upper jaw, and an arcuate strap having its ends secured to said first pivot pin and extending around said thumb wheel.

7. A combined wrench and vise comprising a body member having a shank portion selectively attachable to a handle or mountable in a fixed socket, spaced side arms on said body member defining aligned apertures, a first pivot pin supported in said apertures, a second pivot pin extending between said side arms and spaced from said first pivot pin, a coupling pivotally mounted on said first pivot pin, a thumb wheel defining an internally threaded aperture and having shoulders on its ends, said coupling having opposed nose portions engageable with the shoulders of said thumb wheel, an upper jaw member having a threaded arm portion adjustably received in said thumb wheel, a lower jaw member having a sliding connection with said arm of said upper jaw, a link pivotally connected to said lower jaw and having its lower end pivotally mounted on said second pivot pin, a thrust bar pivotally connected to said coupling and having a shoulder formed thereon, a thrust member rotatably mounted in the side arms of said body, an adjusting screw threadingly engaged with said thrust member, said adjusting screw being movable against said shoulder on said thrust bar, and an arcuate guide member secured to said side arms and concentric about said first pivot pin, said guide member extending through said thumb wheel and alongside of said arm on said upper jaw.

8. A combined wrench and vise comprising a body member having a shank portion selectively attachable to a handle or mountable in a fixed socket, spaced side arms on said body member defining aligned apertures, a first pivot pin supported in said apertures, a second pivot pin extending between said side arms and spaced from said first pivot pin, a coupling pivotally mounted on said first pivot pin, a thumb wheel defining an internally threaded aperture and having shoulders on its ends, said coupling having opposed nose portions engageable with the shoulders of said thumb wheel, an upper jaw member having a threaded arm portion adjustably received in said thumb wheel, a lower jaw member having a sliding connection with said arm of said upper jaw, a link pivotally connected to said lower jaw and having its lower end pivotally mounted on said second pivot pin, a thrust bar pivotally connected to said coupling, a thrust member rotatably mounted in the side arms of said body, an adjusting screw threadingly engaged with said thrust member, said adjusting screw being movable against said thrust bar, and an arcuate strap having its ends secured to said first pivot pin and extending around said thumb wheel.

9. A wrench comprising a body member, spaced pivots carried by said body member, an upper jaw having a threaded arm portion, a thumb nut adjustably receiving said arm on said upper jaw, a guide member engaged with said thumb nut and pivotally connected to one of said pivots, a lower jaw having a sliding connection with said arm of said upper jaw, a link having one end pivotally connected to said lower jaw and its other end pivotally connected to said other pivot on

said body, an abutment rotatably carried by said body and spaced from said pivots, and a threaded clamping member having a threaded engagement with said abutment and movable against said guide member at a point spaced from the pivotal connection of said guide member to swing said guide member about its pivot.

10. A wrench comprising a body member having spaced parallel side arms, an upper jaw having a depending threaded arm, an internally threaded thumb wheel adjustably receiving said arm on said upper jaw, a lower jaw having a sliding connection with said arm on said upper jaw, a link having one end pivotally connected to said lower jaw and its other end pivotally mounted between said side arms on said body, a retaining coupling pivotally mounted between said side arms and spaced from the pivotal connection between said link and said side arms, said coupling being engageable with said thumb wheel to guide said thumb wheel for swinging motion about the pivotal connection of said coupling, an arcuate guide member secured to one of said side arms and concentric about the pivotal connection of said coupling, said guide member extending through said thumb wheel and along side of said arm on said upper jaw, and a retaining band pivotally connected with said coupling for swinging motion concentric therewith, said band being engaged with said thumb wheel for further guiding said thumb wheel.

11. A wrench comprising a body member having spaced parallel side arms, an upper jaw having a depending threaded arm, an internally threaded thumb wheel adjustably receiving said arm on said upper jaw, a lower jaw having a sliding connection with said arm on said upper jaw, a link having one end pivotally connected to said lower jaw and its other end pivotally mounted between said side arms on said body, a retaining coupling pivotally mounted between said side arms and spaced from the pivotal connection between said link and said side arms, said coupling being engageable with said thumb wheel to guide said thumb wheel for swinging motion about the pivot of said coupling, and a retaining band pivotally connected to said coupling for swinging motion concentric therewith, said band being engaged with said thumb wheel for further guiding said thumb wheel.

12. A wrench comprising a body member having spaced parallel side arms, an upper jaw having a depending threaded arm, an internally threaded thumb wheel adjustably receiving said arm on said upper jaw, a lower jaw having a sliding connection with said arm on said upper jaw, a link having one end pivotally connected to said lower jaw and its other end pivotally mounted between said side arms on said body, a retaining coupling pivotally mounted between said side arms and spaced from the pivotal connection between said link and said side arms, said coupling being engageable with said thumb wheel to guide said thumb wheel for swinging motion about the pivot of said coupling, and an arcuate guide member secured to one of said side arms and concentric about the pivotal connection of said coupling, said guide member extending through said thumb wheel and along side of said arm on said upper jaw for further guiding said thumb wheel.

13. A wrench comprising a body member, spaced parallel pivots carried by said body member, an upper jaw having a threaded arm portion, a thumb nut adjustably receiving said arm

portion on said upper jaw, a guide member engaged with said thumb nut and pivotally connected to one of said pivots at a point on said guide member spaced from said arm portion and the axis of said nut, the axis of said one pivot being perpendicular to a plane containing said arm portion and being offset from said arm portion whereby said nut and said arm portion can swing bodily about said one pivot, a lower jaw having a sliding connection with said arm portion of said upper jaw, and a link having one end pivotally connected to said lower jaw and its other end pivotally connected to said other pivot on said body.

15. 14. A wrench comprising a body member having a pivot, an upper jaw having a threaded arm portion, a thumb nut adjustably receiving said arm portion on said upper jaw, a guide member engaged with said thumb nut and arranged to guide said nut and arm portion for arcuate swinging motion about an axis spaced from and parallel to said pivot, said spaced axis being perpendicular to a plane containing said arm portion and passing through said body member in spaced relation to said arm, a lower jaw having a sliding connection with said arm portion of said upper jaw, and a link having one end pivotally connected to said lower jaw and its other end pivotally connected to said pivot on said body.

30. 15. In a wrench, the combination of a body having spaced side members, an outer jaw provided with a threaded shank and having longitudinal grooves in its sides, an inner jaw provided with supporting members engaging said grooves, a supporting link pivotally connected to said inner jaw and between the body side members, said body member having thrust engagement with the link and concentric with the pivot connecting said link to said body member, an adjusting nut for said outer jaw having a peripheral groove, a supporting band embracing the nut and in said groove and pivotally mounted on the body member, curved supports disposed through the nut at the sides of said outer jaw shank and secured at their ends to said body member whereby the jaws are swingably supported on the body member, and an adjusting screw mounted on said body member between the side members thereof and having a thrust connection with the shank of the outer jaw for tiltably moving said outer jaw.

55. 16. In a wrench, the combination of a body having spaced side members, an outer jaw provided with a threaded shank and having longitudinal grooves in its sides, an inner jaw provided with supporting members engaging said grooves, a supporting link pivotally connected to said inner jaw and between the body side members, an adjusting nut for said outer jaw having a peripheral groove, a supporting band embracing the nut and in said groove and pivotally mounted on the body member, a curved support disposed through the nut at the sides of said outer jaw shank and secured at its ends to said body member whereby the jaws are swingably supported on the body member, and an adjusting screw mounted on said body member between the side members thereof and having a thrust connection with the shank of the outer jaw for tiltably moving said outer jaw.

70. 17. In a wrench, the combination of a body having spaced side members, an outer jaw provided with a threaded shank and having longitudinal grooves in its sides, an inner jaw provided with supporting members engaging said

grooves, a supporting link pivotally connected to said inner jaw and between the body side members, an adjusting nut for said outer jaw, a supporting band embracing the nut and pivotally mounted on the body member, a curved support disposed through the nut at the side of said outer jaw shank and secured at their ends to said body member whereby the jaws are swingably supported on the body member, and an adjusting screw mounted on said body member between the side members thereof and having thrust connection with the shank of the outer jaw for tiltably moving said outer jaw.
